CLAIM

The ornamental design for a cap for reusable bottle, as shown and described.

DESCRIPTION

FIG. 1. is a top perspective view of a cap for reusable bottle according to the present invention.

FIG. 2 is a front view of the cap for reusable bottle of FIG. 1.
FIG. 3 is a right side view of the cap for reusable bottle of FIG. 1.

FIG. 4 is a top view of the cap for reusable bottle of FIG. 1; and,

FIG. 5 is a bottom view of the cap for reusable bottle of FIG. 1.

The dashed lines in the figures are for environmental purposes only and form no part of the claimed design.
